April 5, 1960

D. P. HILLIARD

2,931,559

REMAILABLE BILLING ENVELOPES

Filed Aug. 23, 1954

DAVID P. HILLIARD,
INVENTOR.

BY William Jones

ATTORNEY.

may be readily detached from said body portion; transfer material carried on the inner side of said smaller flap whereby any endorsement of record written or inscribed thereon will be reproduced on the inner side of said larger flap; and means for sealing said larger flap over the mouth of said body portion whereby the first mailing address is concealed and the second return mailing address is exposed to view and whereby any extraneous matter placed within said body portion is held securely therein.

References Cited in the file of this patent

UNITED STATES PATENTS

41,804	Woolworth	-----	Mar. 1, 1864
1,201,419	Adams	-----	Oct. 17, 1916
2,196,461	Heywood	-----	Apr. 9, 1940
2,317,335	Whitman	-----	Apr. 20, 1943
2,527,925	Frampton	-----	Oct. 31, 1950

10 FOREIGN PATENTS

505,518	Great Britain	-----	May 12, 1939